JAR COVER WRENCH

Filed April 6, 1931

INVENTOR.
RUDOLPH RATZLAFF

BY

Charles E. Viner
ATTORNEY.

UNITED STATES PATENT OFFICE

RUDOLPH RATZLAFF, OF DEARBORN, MICHIGAN

JAR COVER WRENCH

Application filed April 6, 1931. Serial No. 528,040.

This invention relates to jar cover wrenches and an object of the invention is to provide a wrench for removing from or tightening threaded covers on fruit jars, 5 which comprises only two main pieces and which is so constructed as to permit a great pressure to be applied to the cover to prevent the same from slipping in the wrench.

Another object of the invention is to provide a wrench which is composed of a minimum number of stamped parts thus providing a wrench which is cheap to manufacture and easy to assemble.

Another object of the invention is to provide a wrench composed of one ring like piece provided with an extension forming one handle and further provided with a serrated portion on the inner periphery of the ring portion for gripping the cover and a second piece 20 pivoted at two points to the ring like portion and provided with an extension forming another handle and further provided with a serrated portion for gripping the portion of the cover diametrically opposite to that gripped 25 by the serrated portion on the ring, when the two handles are moved toward each other.

A still further object of the invention is to provide a means whereby the flange on the open end of a jar cover may be straightened 30 so that the same may be used again without permitting any leakage of air between the jar cover and the rubber washer against which it seals.

These objects and the several novel features of the invention are hereinafter more fully described and claimed and the preferred form of construction by which these objects are attained is shown in the accompanying drawing in which—

Fig. 1 is a plan view of my improved wrench.

Fig. 2 is a detail of the movable portion of the wrench.

Fig. 3 is a section taken on line 3—3 of 45 Fig. 1.

Referring now to the drawing it will be seen that the wrench comprises the two main pieces 1 and 2 formed preferably of stampings. The member 1 is provided with the ring like portion 3 and the inner periphery

of the same is provided with the serrations 4 for gripping the cover of a fruit jar (not shown) and is further provided with the notched portion 5 for a purpose to be later described. It will be understood that the inner diameter of the ring like portion 3 is slightly greater in diameter than the outside diameter of the jar cover on which it is to be used, and the inner points of the serrations 4 lie on an imaginary circle the radius of which is approximately equal to the radius of the jar cover so that all of the points of the serrations will grip the cover at the same time. An extension 6 is provided on the outer periphery of the ring 3 providing a handle or grip.

The member 2 is provided with the arcuate portion 7 provided on its edge with the serrations 8, the portion 7 lying in the notch 5 and the serrations 8 on the edge thereof lying in the same plane as the serrations 4 on the inner periphery of the ring like member 3 and positioned diametrically opposite thereto. The portion 15 of the member 2 is depressed an amount equal to the thickness of metal of the member 1 and is provided with the elongated slots 9 and 10 extending at an angle toward each other, and through which the respective pins or rivets 11 and 12, provided in the ring like portion 3, extend. The pins or rivets 11 and 12 being less in diameter than the width of the slots 9 and 10 permit the same to have free movement therein. The member 2 is provided with the extension 13 lying in the same plane as the handle 6 and forms a grip or handle to permit the same to be moved toward the handle 6 when it is desired to grip a cover to tighten or loosen the same on a fruit jar. It will be seen that when the ring like portion 3 is placed over a jar cover that the inner points of the serrations 4 will engage the same and when the handles 13 and 6 are gripped by the hand and the handle 13 moved toward the handle 6 the arcuate portion 7, having the serrations 8 on the edge thereof, will be moved toward the serrations 4 until the same have contacted the cover and by putting additional pressure to bring the two handles 6 and 13 closer together, the jar cover will be tightly gripped.

by the wrench to permit the same to be screwed from or onto a jar onto which it is desired to affix the same.

It will be seen that the pin positioned in the slot 9 permits the member 2 to move freely thereabove and will permit a far greater amount of pressure to be applied to the jar cover than that which is applied to the handles 6 and 13.

10 By referring to Figs. 1 and 3 it will be seen that a plate 20 is secured to one face of the ring like member 3 and is provided on the inner edge with the upturned flange 21. A pair of pins 22 and 23 are also provided upon the 15 same face of the ring like member 3 and form guides to engage the periphery of the flange of the cover and the upturned portion 21 will engage over the flange of the cover and upon rotation of the same under the flange 21 any 20 kinks or irregularities therein will be smoothed out thus permitting the cover to be used a large number of times, as it has been the practice heretofore to discard the covers when the flange on the open end has become 25 irregular, as it is then impossible to properly seal the interstice between the cover and the jar.

From the foregoing description it becomes evident that I have provided a jar cover wrench, which is composed of a minimum number of parts and which is easy to assemble and which will firmly grip a jar cover to remove the same from a jar without any undue pressure being applied to the handles.

30 Having thus fully described my invention, its utility and mode of operation, what I claim and desire to secure by Letters Patent of the United States is—

35 1. A jar cover wrench comprising a closed ring like member provided on one face with a pivot, the inner periphery of the same provided with a gripping edge, a handle extending from the ring like portion, a second member provided with a gripping edge lying in the same plane with the gripping edge on the ring like member, the second member pivotally connected to the pivot on the first member and provided with a handle extending in the same general direction as the first mentioned handle and spaced therefrom so that movement of the handles toward each other will cause the gripping edge on the second member to move toward the gripping edge on the inner periphery of the ring like member.

40 2. A jar cover wrench comprising a ring like member provided on a portion of its inner periphery with a plurality of serrations and further provided with a notched portion substantially diametrically opposite the serrations, a handle extending from the ring like portion, a second member provided with an arcuate portion extending into the notch in the ring like member and provided on its edge with a plurality of serrations lying in the same plane and extending toward the

serrations on the inner periphery of the ring like member, the second member provided with a depressed portion, extending from the arcuate portion, lying in contact with the ring like member, a handle extending from the depressed portion and lying in the same plane as the first mentioned handle, and a pivot extending through the two members so that movement of the handles toward each other will cause the serrations on the arcuate portion of the second member to move toward the serrations on the inner periphery of the ring like member.

45 3. A jar cover wrench comprising a substantially ring like portion provided on a portion of its inner periphery with a plurality of serrations, a notched portion substantially opposite to the serrations, a handle extending from the ring like portion, a pair of pins positioned in the ring like portion and adjacent the edges of the notch therein, a second member provided with an arcuate portion extending into the notch in the ring like member and provided on its edge with a plurality of serrations lying in the same plane and extending toward the serrations on the inner periphery of the ring like member and further provided with a depressed portion 50 extending from the arcuate portion and lying in contact with the ring like member, and provided with a pair of slots through which the respective pins on the ring like member extend, a handle extending from the depressed portion and lying in the same plane as the first mentioned handle, the two members so arranged in relation to each other that movement of the handles toward each other will cause the serrations on the arcuate portion of the second member to move toward the serrations on the inner periphery of the ring like member.

55 4. A jar cover wrench comprising a substantially ring like member, the inner periphery of the same provided with a plurality of serrations, a pair of pivot pins extending from one face of the ring like member, a handle extending from the ring like member, a second member provided on its edge with a plurality of serrations extending toward the serrations on the periphery of the ring like member, and further provided with a pair of slots through which the respective pins on the ring like member extend and a handle extending from the second member and spaced from the handle on the ring like portion so that movement of the handles toward each other will move the serrations on the second member toward the serrations on the inner periphery of the ring like member.

60 5. A jar cover wrench comprising a substantially ring like member, the inner periphery of the same provided with a plurality of serrations, and further provided with a notched out portion, a handle extending from

the ring like member and formed integrally therewith, a pair of pins secured to the ring like member and extending from one face thereof and positioned adjacent each edge of the notch provided in the inner periphery of the ring like member, a second member provided with an arcuate portion extending into the notch in the ring like member and provided on its edge with a plurality of serrations lying in the same plane and extending toward the serrations on the ring like member, the second member provided with a pair of slots extending at an angle toward each other for engagement over the respective pins on the ring like member, a handle formed integrally therewith and extending in the same general direction as the first handle and spaced therefrom, the parts being so arranged that movement of the handles toward each other will move the serrations on the arcuate portion of the second member toward the serrations on the inner periphery of the ring like member.

6. A jar cover wrench, comprising a closed ring like member, the inner periphery of the same provided with a gripping edge, a handle extending from the ring like portion, a second member provided with a gripping edge and pivotally connected to one face of the ring like member and provided with a handle extending in the same general direction as the first mentioned handle and spaced therefrom whereby movement of the handles toward each other will cause the gripping edge on the second member to move toward the gripping edge on the inner periphery of the ring like member.

In testimony whereof I sign this specification.

RUDOLPH RATZLAFF.
